Patented Feb. 21, 1928.

UNITED STATES PATENT OFFICE.

JOHN WARE, OF PINEVILLE, KENTUCKY.

CAR-PIPE COUPLER.

Application filed February 18, 1927. Serial No. 169,286.

This invention relates to a pipe coupling for railroad trains, the general object of the invention being to provide automatic means for coupling together the train pipes as two cars are coupled together, so that it is not necessary for the trainmen to couple said pipes.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a fragmentary side view of a pair of cars showing the invention in use.

Figure 2 is a section on line 2—2 of Figure 1.

Figure 3 is a section on line 3—3 of Figure 1.

Figure 4 is a section on line 4—4 of Figure 1.

Figure 5 is an enlarged sectioned view through one of the coupling means showing the pipes in section.

Figure 6 is a sectional view showing the valve means of two pipes in closed position and just before the parts assume a position where the valves will be opened.

As shown in these views, I place a depending bracket 1 on each end of each car in which is rotatably arranged a block 2 which has its trunnions 3 positioned so that the block can rotate about a vertical axis. Each block has an arm 4 which is connected with opposite sides of the bracket by the springs 5, these springs tending to hold the block in its middle position. A square shank 6 passes horizontally through the block and a coupling head 7 is carried on the outer end of each shank. A coil spring 8 is arranged between the head and the bracket and tends to hold the head and shank extended, but will permit the head and shank to move toward the center of the car when another head strikes the first head. Each head is of substantially conical form, with its base outermost so that a flaring socket is provided in the head which acts as a guide for the pipe of the other car when two cars are moving to coupling position. Each head is di-

vided in half, with the half 7' hingedly connected with the stationary part of the hinge 9, this hinge being a spring one, so that the part 7' normally remains in contacting relation to the stationary part. The hinge part 7' has an opening 10 therein in which is arranged a shouldered member 11 which is normally held in its innermost position by

the coil springs 12 on the bolts 13 which also act as guides for the member 11.

A valve casing 14 is carried at the inner end of the socket of each head and this casing is connected by a pipe 15 which passes through the shank 6, with the flexible pipe 16 which is connected with the train pipe. Each casing carries a valve 17 which is normally held upon its seat 18 by a spring 19, the outer end of the stem of the valve being beveled, as shown. An extension pipe 20 is

connected with an extension of the casing by means of a flexible tube 21, so that the extension pipe 20 is flexibly connected with the casing and the extremity of this extension 20 is also provided with a valve casing 22

which carries a valve 23 which is a duplicate of the valve 17 and the stem of this valve 23 is also beveled so that when a valve in an extension 20 comes opposite a valve in the casing 14 of another car, the two valves will be opened so that fluid can pass from one car to the other. The parts are provided with suitable gaskets 24 to make a tight joint when the two parts come together. The casings are provided with rounded parts 25 so

that as the rounded part on one casing engages the rounded part on the other, the casings will move apart and in this movement the hinge sections will be moved outwardly and then as the rounded parts pass each other, the spring hinges will force the sections closed and firmly press a casing 22

against the casing 14 so that the valves will be opened. The parts will be held in coupling position by the shoulder on member 11

engaging the rear part of the casing 22. 100

From the foregoing, it will be seen that I have provided means whereby train pipes will be automatically coupled together when the cars are moved to coupling position and

as soon as the cars are uncoupled, the parts of the pipe coupling will automatically separate as the hinge sections will be raised by the pressure of the casing 22 on the shouldered member 11 to permit the extension 110 pipe 20 of one coupling element to pass out of the coupling head of the other element.

It is thought from the foregoing description that the advantages and novel features of my invention will be readily apparent.

I desire it to be understood that I may 5 make changes in the construction and in the combination and arrangement of the several parts, provided that such changes fall within the scope of the appended claim.

What I claim is:—

- 10 11 A pipe coupling for cars comprising a head having a flaring mouth, said head being formed in sections, one section being hingedly connected with the other, a spring connected with the hinge, a spring pressed 15 shouldered member carried by the hinge section, a valve casing in the head, a spring

pressed valve controlling the outlet of the casing, means for connecting the casing with a pipe on the car, an extension pipe flexibly connected with the casing, a valve casing at 20 the end of the extension pipe, a spring pressed valve closing the outlet of the same, the outer ends of the stems of said valves being beveled so that when two stems come together the valves will be opened by the 25 pressure of the spring hinge section against the casing on the extension pipe, the shouldered member acting to lock the extension pipe of one car in the head of another car.

In testimony whereof I affix my signature,

JOHN WARE.
